Attorney

UNITED STATES PATENT OFFICE

JULIUS KAHN, OF JERSEY CITY, NEW JERSEY, ASSIGNOR TO DU PONT VISCOLOID COMPANY, OF WILMINGTON, DELAWARE, A CORPORATION OF DELAWARE

BARRETTE

Application filed January 30, 1931. Serial No. 512,336.

This invention relates to holding devices, and more particularly to holding devices for the hair in the character of barrettes. While not restricted thereto the invention has more particular application to barrettes decorated with cellulose ester plastic, for example pyroxylin plastic.

In the field of pyroxylin plastic articles it is necessary, in a large class of these articles such as barrettes and similar items of adornment, to produce them in such manner that although they embody in their construction an assembly of a metallic body and plastic decorative material therefor, they may be produced at a minimum cost, and consequently sold at a minimum price. I have provided a barrette in which plastic decorative material is combined with a metallic body in such manner that the article may be satisfactorily produced at low cost, the resulting article being efficient and rugged.

One object of the invention is to provide a holding device having the desirable characteristics above mentioned. To this end and also to improve generally upon devices of the character indicated and methods of producing the same the invention consists in the various matters hereinafter described and claimed.

Without restricting the invention thereto the same is described by reference to the embodiments thereof illustrated in the accompanying drawing. In the drawing Fig. 1 is a side view of a barrette embodying the invention; Fig. 2 is a cross sectional view taken on substantially the line 2—2 of Fig. 1; and Figs. 3, 4 and 5 are cross sectional views of slightly modified forms of the invention.

Referring now in detail to the drawing, the barrette comprises a body designated generally as 1 and composed of the back 2 and the tongue 3, the body being, preferably, of spring metal with the tongue given a permanent bias toward pressing against the back 2. Carried upon the exterior face of the back 2 is a body of decorative plastic 4, this plastic embodying its decorative features in any suitable way as by its coloring, or by including metallic particles therein or stuck thereto, and so on. Wrapped about the plastic

body 4 and the back 2 is an envelope of transparent plastic 5, the envelope serving to permanently attach the decorative body to the back while not interfering with the exposure of the body 4 to view. As will be understood by those skilled in the pyroxylin plastic art the envelope 5 may be tightly rolled about the back 2 and the body 4 while the sheet or strip of plastic forming the envelope is warmed to give it a temporary flexibility, whereupon, upon cooling, the envelope remains permanently set in its wrapped form and tightly and permanently assembles and holds together the back 2 and the body 4. If desired, of course, a suitable cement, e. g. a pyroxylin cement, may be used between any or all of the parts of the assembly.

The detailed character of the assembly may, of course, be widely varied. Thus, as illustrated in Fig. 2, the envelope may be in the character of a strip or sheet which although it "hooks under" the back 2 does not completely envelop it; or, as illustrated in Fig. 3 the envelope may be in the character of a previously-made tube into which the back 2 and the body 4 are slipped while the envelope is warm and stretched slightly, whereupon, upon cooling the tube shrinks upon the back and body. Also the back 2 and the body 4 may be of any desired cross sectional configuration provided they present a sufficient area for contact with the envelope 5. Thus, as illustrated in Fig. 4 the body 4 may be of a cross sectional shape other than rectangular, as by having an arched top surface 4^a; or, as illustrated in Fig. 5, the envelope need not clasp the top surface of the body 4, sufficient contact being obtained along the sides and bottom of the members 2 and 4. Many other variations embodying the invention will, of course, suggest themselves to those skilled in the art.

In making the decorative body 4 of the barrette decorative plastic of any suitable composition, e. g. parts by weight pyroxylin 23.6, camphor 8, urea .1, pigment (finely divided variously colored metallic flakes) 1, residual solvent (alcohol) .3 is made up in any of the usual ways of making pyroxylin plastic stock and is cut to suitable dimensions for

the purpose. The transparent material for the envelope 5 may be similarly prepared, except that, obviously, it should not contain sufficient pigment (if any) to materially detract from its transparency, although it may be dyed any suitable color if desired. The block of stock 4, and the sheet (or tube) of stock 5 having been thus prepared they may be assembled with the metal member, as previously mentioned. Although the member which has, for definiteness, been particularly described as of metal, it will be plain that it may be of other spring material, as indeed, pyroxylin plastic having a suitable resiliency and permanent set. Furthermore, it will be seen that certain of the advantages of the invention may be obtained even though the envelope 5 is not transparent. For example, a construction in accordance with the invention may be used to build up a back of proper thickness for a barrette from a proper backing with a body of plastic carried thereon.

I claim:

1. A barrette comprising a cooperating tongue and back, a body of decorative material carried upon said back, and an envelope of transparent material over-lying said decorative material and engaging said back to hold said decorative material upon said back.
2. A barrette comprising a cooperating tongue and back, a body of decorative pyroxylin plastic carried upon said back and extending substantially throughout the length thereof, and an envelope of transparent pyroxylin plastic over-lying said decorative material throughout substantially the length thereof and under-lying said back, to hold said decorative plastic upon said back.
3. A decorated barrette comprising, a metal barrette proper presenting a tongue and a back, a decoration for said barrette proper in the form of a strip of cellulosic plastic carrying a decorative material therein as an element of the composition thereof, said strip lying along said back on the exterior thereof, and an envelope of transparent cellulosic plastic enveloping said strip and back to hold said decoration assembled upon said back while exposing said decoration to view.

In testimony whereof, I affix my signature.
JULIUS KAHN.
